Specification of Letters Patent.

Patented Mar. 8, 1921.

Application filed March 25, 1920. Serial No. 368,500.

To all whom it may concern:

Be it known that I, CHARLES A. NELSON, a citizen of the United States of America, and residing in the city of Utica, county of 5 Oneida, State of New York, have invented certain new and useful Improvements in Firearms, of which the following is a specification.

My invention relates to take-down guns, 10 especially to repeating guns in which there is a magazine tube parallel with the barrel which performs the functions of the locking member as well as the functions of the magazine and which carries a sliding grip 15 or action handle for actuating the breech mechanism.

The objects of my invention are to provide novel and improved mechanism whereby the magazine tube or other similar barrel 20 locking member may be readily moved from its locking to its unlocking position and vice versa, whereby it is simply locked in each of these positions, whereby the action handle is held in a forward position when 25 the gun is taken down, whereby in taking down the gun the mechanism is necessarily though quite naturally manipulated in a certain sequence which leaves the parts in the proper positions for reassembly, and 30 whereby the magazine tube is simply though firmly carried by the barrel. These and other features that will be apparent to those skilled in this art are also provided by this invention.

35 In the two sheets of drawings which illustrate the best embodiment of my invention of which I am now aware; Figure 1 is an elevation, partly in section, of the barrel part of the firearm in place in the receiver. 40 Fig. 2 is a similar figure of the same device showing the magazine separated from the receiver but with the barrel still in place therein. Fig. 3 is a sectional view on the line 3-3 of Fig. 2 looking in the direction of 45 the arrows. Fig. 4 is a sectional view on the line 4-4 of Fig. 2 looking in the direction of the arrows. Fig. 5 is an elevation of the barrel section of the gun, this section being entirely separated from the receiver. 50 Fig. 6 is an elevation of the forward end of the receiver. Fig. 7 is an elevation of the rear end of the barrel clip. Fig. 8 is an elevation of the forward end of the magazine tube showing, particularly, a part of the 55 locking means therefor. Fig. 9 is a detail

view of the magazine lever and its coöperating mechanism, and Fig. 10 is another detail.

The forward end of the receiver of the arm illustrated is shown at 1; the hammer, breech-bolt, cartridge carrier and various coöperating and other mechanism of the arm are contained within the receiver as will be readily understood. 2 is the barrel carrying the magazine tube 3. Screw-threaded into the forward end of the receiver is the ordinary compensating nut provided internally with mutilated screw threads 4 for engaging similar mutilated threads 5 on the rear end of the barrel. These screw threads are disposed in quite the common manner, viz., 70 there are two sets of threads on the barrel diametrically opposite each other and each extends substantially one-quarter of the way around the barrel; the screw threads of the receiver correspond. Accordingly it follows 75 that the barrel may be attached to the receiver by two movements, first by straight insertion, the two sets of threads on the barrel passing between the two sets of threads on the receiver, and then by a quarter turn 80 of the barrel with respect to the receiver whereby the threads on the two parts are engaged. In the receiver and immediately below the opening thereof for the reception of the barrel 2, there is provided a second 85 opening for receiving the rear end of the magazine tube 3. This opening in the receiver and the rear end of the magazine tube 3 are also provided with mutilated screw threads for locking the magazine tube to 90 the receiver in substantially the same manner as the barrel is locked to the receiver. The groups of magazine tube threads are however, in the instance illustrated, disposed substantially at right angles to the 95 groups of threads of the barrel; that is, when the barrel is locked in the receiver, its threads are at the top and the bottom thereof, whereas when the magazine tube is locked to the receiver its threads are opposite the 100 sides of the receiver; however, substantially any other arrangement is suitable for my invention. To the rear end of the barrel is attached the barrel clip 6; in the present instance this clip is screw-threaded to the 105 barrel. The lower part of this clip receives the rear end of the magazine tube 3 and is considerably longer than the part receiving the barrel, its required length being indicated hereinafter. Before proceeding far- 110

ther it is well to note that the magazine tube 3 is the means for locking the barrel 2 in the receiver. When the magazine tube is seated in the receiver it prevents the rotation of the barrel 2 to its unlocking position. To remove the barrel, the tube 3 must first be rotated a quarter turn (from its position in Fig. 1) and then moved longitudinally forward until its rear end leaves the receiver 1 though still contained in the clip 6. Thereafter the whole barrel part, including the barrel, magazine tube and barrel clip, may be rotated to release the barrel from the receiver (presuming that the action bar, if 15 there is one as later described, has also been withdrawn from the receiver).

Surrounding and sliding on the magazine tube 3 is the action handle or grip 7 by which the gun is operated. This action 20 handle comprises a main metallic sleeve or tube section 8 and a supplementary metallic tube section 9 united in such manner as to provide an internal ring or collar 10, the forward face of which forms a shoulder 10^a 25 and the rearward face a shoulder 16, both within the grip. These united shells or tubes form the frame of the handle, being covered with a cylinder 12 of wood or other suitable material, grooved to provide a grip 30 surface. The handle section 9 is fixed to or formed integrally with the action bar 11, which, as will be understood, extends rearwardly through the hole 48 in clip 6 and into the receiver 1 for operating the mechanism contained therein. A collar 15 is 35 fixed on the magazine tube 3 for engagement with the shoulder 10^a to limit the forward movement of the handle on the tube and a lug 17 is also provided on the magazine tube 40 to engage the shoulder 16. The collar 15 and the lug 17 are adapted to receive the ring 10 of the handle between them with a fairly snug fit, and the ring 10 is formed with a longitudinal slot 20 which is so 45 disposed that when the magazine tube is locked into the receiver, that is, has been rotated to its final locking position, the lug 17 registers with the slot 20 as seen in Fig. 1. In this position, which is the normal working 50 position of the gun, the action handle 7 may be moved back and forward on the magazine tube, the slot 20 passing over the lug 17. If, however, the magazine tube 3 be rotated to carry the lug 17 out of register with the slot 55 and opposite the shoulder 16, as shown in Fig. 2 the action handle 7 is then locked in its longitudinal position on the magazine tube 3. Such rotation occurs as the first step in disassembling the gun, to release the 60 threads of the magazine tube from those on the receiver, and by thus locking the tube to the handle the latter may be used to withdraw the tube from and reenter it in the receiver, as though the two parts were one. 65 It will be obvious that, by simple reversal,

the lug 17 could be carried by the handle and the slot 20 by the tube, if desired, and provide the same functions. The magazine tube is slidably mounted at its rear in the clip 6, as above stated, and at its front in the assembly clip 24 fastened to the gun barrel, and a lug 23 formed on the magazine tube engages with the rear end of this assembly clip to limit the forward or withdrawing movement of the magazine tube as 70 indicated by Fig. 2 which shows the handle in its forward position on the tube and the tube in its forward position on the barrel. The assembly clip 24 is a circular band embracing the tube and provided with a dove-tail 26 engaging a dove-tail slot 27 fixed transversely on the gun barrel. The dove-tail and its slot are correspondingly tapered, and a headed screw 28 is threaded into the small end of the dove-tail 26 with its head 80 engaging the corresponding end of the dove-tail slot so that by tightening the screw the parts are firmly seated and united. The assembly clip 24 coacts with the magazine tube to compel a predetermined and proper sequence of steps in taking the gun down. For this purpose it is provided at its forward edge with two integral and forwardly projecting shoulders 31 and 32 and with a notch 33 adjacent the first of these shoulders. 90 The magazine lever 36 by which the magazine tube may be rotated, is pivoted at 38 in the forward end of the magazine tube, and provided with a spring-detent 39 to retain it in its extreme angular positions in one 100 of which it is transverse to the tube and in the other parallel to it and pressed against it as indicated by the dotted and full lines in Fig. 1. When the gun is assembled and the lever is brought to the position indicated in 105 Figs. 1 and 9, a part of the lever near its pivot enters within the notch 33 of the clip and thereby prevents rotation of the tube until the lever is opened or swung to a transverse position. The opening of the magazine lever is thus the first step in rotating the tube to unlock it. When thus opened its heel 37 swings through the notch 33 to the position shown in Fig. 8 where it coacts with the lug 32 to limit the opening rotation of 110 the tube and with the lug 31 to limit its reverse rotation. The extent of such rotation is sufficient to engage and disengage the threads of the tube with those of the receiver, and it will be observed that the overhanging of the heel above the edge of the clip obstructs the closing of the lever unless the tube is screwed fully home, so that the heel may enter the notch 33. 115

The assembly clip 24 is also provided with 120 a longitudinal spline groove 40 (Fig. 4) to engage a corresponding spline 41 on the magazine tube 3 (see also dotted lines of Fig. 1). This anti-rotation locking arrangement permits of a simple construc- 130

tion; for example, on the part of the magazine, the tube may be of drawn steel from which the spline is raised by a simple pressing operation. This spline is so disposed 5 on the tube 3 that when the latter is in its locking position (Fig. 1) the spline is a quarter turn displaced from the spline groove 40, but when the tube 3 is rotated to unlock it from the threads of the receiver 10 (to the extent limited by the abutment of 37 upon 32,) the spline 41 registers with its groove. The tube being then moved forwardly, the spline will enter its groove and its length substantially equals the forward 15 traverse of the tube so that so long as the tube is forward it can not be rotated.

Thus the take down action depends on three successive manipulations which can only be performed in a single sequence. 20 First, the lever 36 must be opened, the tube must then be turned, and then withdrawn from the receiver. These manipulations can be carried on in no other sequence for the withdrawal of the tube depends on its rotation and its rotation depends on its being released by the lever. In the reassembly 25 the sequence is reversed, the spline prevents tube rotation until the tube is fully inserted in the receiver and the lever can not be closed against the tube until the tube is 30 fully screwed into the receiver.

Figs. 6 and 7 show, respectively, the forward end of the receiver 1 and the rear end of the barrel clip 6 as to which it may be 35 noted that the opening 48 in the barrel clip registers with the hole 47 in the receiver, these being for the passage of the action rod 11 as will be understood. The screw 49 secures the key 50 which locks the compensating 40 nut which carries the mutilated threads 4 of the receiver above referred to. A curved slot 52 in the rear face of the barrel clip 6 provides clearance for the head of the screw 49 as the barrel is placed in the receiver. 45

The operation of the gun is as follows: Starting with the fully assembled position shown in Fig. 1, it will be understood that the magazine tube 3 carries a supply of cartridges and that suitable mechanism forces 50 these cartridges to the rear as the receiver mechanism will accept them. After the gun is fired, the action handle 7 is moved to the rear carrying the action bar 11 therewith; 55 this in its turn causes the used shell to be ejected and the hammer cocked. The return of the action handle 7 forward causes a fresh cartridge to be placed in the barrel and the receiver mechanism returned to the 60 firing position. In this movement of the handle, as before pointed out, the slot 20 in the ring 10 within said handle passes over the lug 17 on the tube and this relation is 65 preserved as long as the tube is in its full home position in the receiver. The slightest

reverse rotation of the tube will carry the lug 17 out of registry with the slot 20 and thereby obstruct the movement of the action handle and thus give notice of the incomplete assembly; as long as the lever 36 is closed into the notch 33 such reverse rotation is prevented and the parts will function as described. Now if the gun is to be taken down the lever 36 is first opened to the transverse position shown in dotted lines 70 in Fig. 1. This withdraws the lever from the notch 33 and allows rotation of the magazine tube. Using the lever 36 as a handle, the tube 3 is then rotated until the now projecting heel 37 strikes the rotation 75 limiting shoulder 32 on the assembly clip 24. The length of the lever 36 provides ample leverage for unscrewing the tube and the shoulder 32 stops it only when the mutilated threads are fully disengaged. Coincidentally 80 with such rotation of the magazine the lug 17 is disaligned with the slot 20 and thereby locks the action handle 7 to the tube 3 as before pointed out, so that by grasping the lever 36 or action handle 7 both may now be 85 pushed forwardly until the lug 23 strikes the assembly clip 24. This withdraws the action bar from the receiver, the said lug 23 being so located as to engage the clip just after the rear end of the bar leaves the 90 opening 47 in the receiver. Accordingly, the rear end of the action bar is left standing in the hole 48 and the tube in the barrel clip 6. The same forward motion enters 95 the spline in its spline groove as above explained so that the tube is susceptible of no further rotary movement. The lever 36 may now be swung from its open position (shown in dotted lines in Fig. 2) until it again lies against or along the tube 3. The 100 lever's length equals or is slightly greater than the longitudinal traverse of the tube 3 so that when in this position, with the tube forward, its free end engages the forward edge of the assembly clip 24 and thereby 105 positively obstructs the return of the magazine tube rearwardly. The detent-spring urges the lever against the tube and thus holds it in this obstructing position. With the magazine tube thus forward the 110 barrel may be removed from the receiver by a quarter turn of the whole barrel part or section of the arm, as above explained. To reassemble the gun the reverse sequence is followed; that is, the barrel is first seated in 115 the receiver, then 36 is opened, the magazine moved longitudinally into the receiver, then rotated until the lever projection 37 strikes the rotation limiting shoulder 31 and finally 120 the lever 36 is closed.

While I have thus illustrated and described the best embodiment of my invention of which I am now aware, it will be understood that this embodiment is merely 125 illustrative and that my invention is not 130

limited thereto, but includes various modifications and alterations in the shape, arrangement and relative positions of the several parts and reversals and substitutes 5 thereof within the meaning of the following claims.

Claims.

1. A take-down gun comprising a receiver, a barrel, a magazine tube parallel 10 with the barrel and rotatable and slidable longitudinally with respect to the barrel to unlock the latter, an assembly clip embracing the magazine and carrying the same on the barrel, and an action handle normally 15 slidable on the magazine tube, combined with means operable by the unlocking rotation of said tube to prevent the sliding of the handle with respect to the tube, a spline projecting from and extending longitudinally 20 of the magazine tube, and a longitudinal groove in the assembly clip to receive the spline when the magazine tube is rotated and moved longitudinally to unlock the barrel, whereby the action handle is held from 25 sliding on the magazine tube and the tube is held against rotation until said tube is returned longitudinally to its locking position.
2. A take-down gun comprising a receiver, a barrel, a barrel locking magazine 30 tube rotatable in the act of unlocking the barrel and an assembly clip embracing the magazine and affixed to the barrel, the assembly clip having rotation limiting shoulders on an edge thereof and a notch, and 35 the magazine tube having an element movable into and from the notch to prevent the rotation of the tube and also adapted to abut against said rotation limiting shoulders to limit the rotary movement of the 40 tube.
3. A take-down gun comprising a receiver, a barrel, a barrel locking magazine tube rotatable less than a complete turn to unlock the barrel, an assembly clip uniting 45 the magazine and barrel, said clip having rotation limiting shoulders on its forward edge and a notch, and a lever pivoted to the magazine and adapted to enter said notch when the lever is closed and adapted also to 50 engage with said rotation limiting shoulders to limit the rotary movement of the tube when the lever is opened.
4. A take-down gun comprising a receiver, a barrel, a barrel-locking member 55 parallel therewith and rotatable in the act of unlocking the barrel, and a fixed member on the barrel extending over said parallel member, the fixed member having rotation limiting shoulders on an edge thereof and a 60 notch, and the locking member having an element movable into and from the notch to prevent the rotation of the tube and adapted to abut said rotation limiting shoulders to limit the rotary movement of the locking 65 member.

5. A gun as described in claim 2 in which the barrel is completely unlocked by sliding the magazine tube longitudinally after the rotation thereof, further characterized by the free end of the lever engaging the clip 70 when the magazine tube has been moved longitudinally to its unlocking position and the lever has been closed to hold the magazine tube in such position.

6. A take-down gun comprising a receiver, a barrel, a magazine tube on the barrel and rotatable and slid able longitudinally to unlock the barrel, an assembly clip fixed to the barrel and embracing the magazine tube, said assembly clip having rotation 80 limiting shoulders on its forward edge and a notch adjacent one of the shoulders, an action handle normally slidable on the magazine tube, and means operable by the unlocking rotation of said tube to prevent the 85 sliding of the handle with respect to the tube, in combination with means operable after the tube is rotated and moved longitudinally to unlock the barrel, to hold the tube against rotation until the tube is returned to its locking position, and means on the magazine tube movable into and from said notch to prevent the rotation of the tube and adapted to engage with said rotation limiting shoulders to limit the rotary 90 movement of the tube.

7. A take-down gun comprising a receiver, a barrel, a magazine tube parallel therewith and rotatable and slid able longitudinally with respect to the barrel to unlock the latter, an assembly clip fixed to the barrel and embracing the tube and having a spline and groove connection with the tube whereby when the tube is rotated and moved longitudinally to unlock the barrel the tube 105 is held against rotation until returned longitudinally to its locking position and also having rotation limiting shoulders on its forward edge and a notch adjacent one of the shoulders, and a lever pivoted to the 110 magazine and having a part to lay in said notch when the lever is closed and adapted to engage the said rotation limiting shoulders to limit the rotary movement of the tube when the lever is open, the free end of the lever engaging the clip when the magazine has been moved longitudinally to its 115 unlocking position and the lever is depressed, to hold the magazine tube in such position.

8. A take-down firearm comprising a receiver, a barrel, a barrel locking magazine tube rotatable and slid able longitudinally to lock and unlock the barrel, means fixed to the barrel embracing the tube and providing 125 fixed rotation limiting shoulders, means on the tube to abut said shoulders to limit the rotation of the tube and in combination with a spline and groove connection between the first mentioned means and the tube to pre- 130

vent the rotation of the tube when the tube is displaced longitudinally from its locking position.

9. A take-down firearm comprising a receiver, a barrel, a barrel locking magazine tube rotatable and slidably longitudinally to lock and unlock the barrel, means fixed to the barrel embracing the tube and providing fixed rotation limiting shoulders, means on the tube to abut said shoulders to limit the rotation of the tube, and releasable means to prevent the rotation of the tube from its locking position, in combination with a spline and groove connection between the first mentioned means and the tube to prevent the rotation of the tube when the tube is displaced longitudinally from its locking position.

10. A take-down firearm comprising a receiver, a barrel, a barrel locking magazine tube rotatable and slidably longitudinally to lock and unlock the barrel, means fixed to the barrel embracing the tube and providing fixed rotation limiting shoulders, means on the tube to abut said shoulders to limit the rotation of the tube, and releasable means to hold the tube from sliding from its unlocking position, in combination with a spline and groove connection between the first mentioned means and the tube to prevent the rotation of the tube when the tube is displaced longitudinally from its locking position.

11. A take-down firearm comprising a receiver, a barrel, a barrel locking magazine tube rotatable and slidably longitudinally to lock and unlock the barrel, means fixed to the barrel embracing the tube and providing fixed rotation limiting shoulders, means on the tube to abut said shoulders to limit the rotation of the tube, releasable means to prevent the rotation of the tube from its locking position, and releasable means to hold the tube from sliding from its unlocking position, in combination with a spline and groove connection between the first mentioned means and the tube to prevent the rotation of the tube when the tube is displaced longitudinally from its locking position.

12. A take-down firearm comprising a receiver, a barrel, a barrel locking magazine tube rotatable and slidably longitudinally to lock and unlock the barrel, and releasable means to hold the tube from sliding from its unlocking position, in combination with

means fixed to the barrel embracing the tube and provided with a spline and groove connection between the same and the magazine tube to prevent rotation of the tube when the tube is displaced longitudinally from its locking position.

13. A take-down firearm comprising a receiver, a barrel, a barrel locking magazine tube rotatable and slidably longitudinally to lock and unlock the barrel, in combination with means fixed to the barrel and provided with a spline and groove connection between the same and the tube to prevent rotation of the tube when the tube is displaced longitudinally from its locking position, and a lever on the magazine tube adapted when closed to engage said means to hold the tube so displaced.

14. A take-down firearm comprising a receiver, a barrel, a barrel locking magazine tube slidably longitudinally to lock and unlock the barrel, and means fixed to the barrel embracing the tube, in combination with a lever pivoted to the tube and engaging with said means when the magazine is in unlocking position and the lever is closed against the outside of the tube to hold the tube in such position.

15. A take-down firearm comprising a receiver, a barrel, a barrel locking magazine tube slidably longitudinally to lock and unlock the barrel, and means fixed to the barrel embracing the tube, in combination with a lever pivoted to said tube in front of said means and adapted to engage its rear end with said means when the magazine is in unlocking position and the lever is closed against the outside of the tube to hold the tube in such position.

16. A take-down firearm comprising a receiver, a barrel, a barrel locking magazine tube rotatable and slidably longitudinally to lock and unlock the barrel, an action bar normally slidable on the magazine tube, and means operable with the rotation of the tube to lock the action bar against sliding on the tube, in combination with means fixed to the barrel embracing the tube and provided with a spline and groove connection with the tube to prevent the rotation of the tube when the tube is displaced longitudinally from its locking position.

In testimony whereof I have signed this specification.

CHARLES A. NELSON.
